ELECTRODE SPACING REGULATOR UTILIZING A NONLINEAR REFERENCE IMPEDANCE DEVICE

Didier Journeaux, Wauwatosa, Wis., assignor to Allis-Chalmers Manufacturing Company, Milwaukee, Wis.

Original application March 8, 1947, Serial No. 733,343, now Patent No. 2,539,912, dated January 30, 1951. Divided and this application July 1, 1950, Serial No. 171,771

11 Claims. (Cl. 314—64)

1

This invention relates in general to improvements in electric control systems, and more particularly to means for regulating the spacing of consumable electrodes between which current flows through a gaseous or liquid medium. This application is a division of my Patent No. 2,539,912.

Electric current may be caused to flow between a pair of working electrodes through a fluid medium for different purposes such as electrolysis of salts, fusion and refining of metals, or chemical reaction between gases. The flow of current or discharge may take place over a wide range of spacings between the electrodes, but under a given set of operating conditions it is generally found advantageous to maintain the electrode spacing substantially constant. When the electrodes are of a consumable type, it is therefore necessary to readjust their spacing from time to time.

As it is generally not feasible to measure the spacing between the electrodes, the electrode actuating apparatus is frequently controlled in response to the current intensity through the electrodes. The action of such control is based on the assumption that there is a uniform relation between the current intensity and the electrode spacing, and it is therefore disturbed by fluctuations in the voltage of the source supplying current to the electrodes. In polyphase furnaces the current intensity through each pair of electrodes is also dependent upon the spacings of the other pairs of electrodes, so that inaccurate spacing of one pair of electrodes results in unnecessary and improper readjustments of the other pairs.

The above disadvantages may be obviated by controlling the spacing of each pair of working electrodes in accordance with the relative values of the voltage across the electrodes and of the voltage of a suitable standard of reference. The latter may consist of any suitable means or combination of means having a volt-ampere characteristic substantially matching the volt-ampere characteristic of the discharge between electrodes maintained at the desired spacing.

When the discharge between the electrodes has a nonlinear drooping volt-ampere characteristic, any type of standard of reference having a drooping volt-ampere characteristic may be utilized over a limited range of currents. To obtain the desired electrode spacing over a wide range of currents, the standard of reference should have a nonlinear drooping volt-ampere characteristic.

The system claimed in the above identified patent, which utilizes a pair of reference electrodes as a standard of reference, provides a highly ac-

2

curate and sensitive control for maintaining the desired spacing. However, the volt-ampere characteristic of a given pair of reference electrodes is relatively fixed and consequently in such a system special means must be provided to accurately accommodate for working arcs having varying shapes of volt-ampere characteristics. An additional disadvantage of such systems is that the reference electrodes have a limited life.

These disadvantages can be overcome by utilizing as a standard of reference, means which are extremely rugged and durable and whose volt-ampere characteristic may be readily varied to accommodate working arcs having varying shapes of volt-ampere characteristics. One of the most suitable of such reference standards is a circuit comprising a source of constant voltage associated with an adjustable nonlinear impedance device having a rising characteristic and traversed by current proportional to the current of the working electrodes. The voltages of the working electrodes and of the standard of reference are measured by suitable indicating instruments or measuring circuits, and the spacing of the working electrodes is varied, either manually or by suitable responsive means, in accordance with the relative values of the measured voltages.

It is therefore an object of this invention to provide a system for regulating the spacing of a pair of electrodes which is extremely rugged and durable.

It is a further object of the present invention to provide a system for regulating the spacing of a pair of electrodes which is accurate for electrodes carrying arcs having varying shapes of volt-ampere characteristics.

It is an additional object of the invention to provide an improved system for regulating the spacing of a pair of arcing electrodes utilizing a standard of reference having a volt-ampere characteristic matching the volt-ampere characteristic of the arc.

Objects and advantages other than those above set forth will be apparent from the following description when read in connection with the accompanying drawing, in which:

Fig. 1 diagrammatically illustrates one embodiment of the invention for regulating the spacing of a pair of electrodes of a polyphase arc furnace, in which embodiment a nonlinear resistor is utilized as an element of the standard of reference for controlling the electrode hoist motor through an electric valve;

Fig. 2 diagrammatically illustrates an alter-

nate embodiment of the invention in which one element of the standard of reference is a nonlinear reactor; and

Fig. 3 is a graph of the volt-ampere characteristics of the working electrodes and of the elements of the standard of reference.

Referring more particularly to the drawing by characters of reference, numerals 11, 12, 13 designate electrodes of an electric furnace 14 of the polyphase arcing type. Current is supplied to the electrodes from a suitable source of alternating current represented as a three-phase distribution circuit 15 connected with the electrodes through suitable current limiting means such as reactors 16. The furnace contains a pool of molten metal 17 serving as an intermediate electrode of which different portions cooperate with electrodes 11, 12, 13 to constitute three pairs of electrodes.

Electrodes 11, 12, 13 are severally provided with hoisting means for maintaining the electrodes at a constant distance from pool 17. The hoisting means may be actuated manually, or each electrode may be provided with a hoist motor such as an electric motor 18 of the direct current type having an armature 19 connected with the electrode through a shaft 20.

The operation of the hoisting means of electrode 11 is controlled in dependence upon the relative values of the voltage across electrodes 11, 17 and of the voltage across a suitable standard of reference. The volt-ampere characteristic of the standard of reference should be generally similar to the volt-ampere characteristic of the arc drawn between electrodes 11, 17 and should therefore generally be drooping when the discharge between electrodes 11, 17 is of the type designated as an arc. To obtain a control of maximum accuracy the volt-ampere characteristic of the standard of reference should further be nonlinear.

The standard of reference may consist of a circuit comprising an adjustable nonlinear resistor 21 and a source which may be adjusted to operate at different values of constant voltage. The currents in the standard of reference and in the voltage measuring circuits may be of any suitable form. If the measuring circuit is to be operated on direct current, a battery 22 may be utilized as the source of constant voltage. Means are provided to supply to resistor 21 current of any suitable form and of intensity in a predetermined relation to the current intensity through electrodes 11, 17 and through the arc established therebetween. For example, resistor 21 may be supplied with current proportional to the current of electrodes 11, 17 from the secondary winding of an adjustable current transformer 23 having its primary winding serially connected with electrode 11. The voltage across resistor 21 is measured by a circuit which, if it is operated on direct current, may comprise a rectifier 25 of any suitable known type, a suitable current smoothing means such as a series reactor 26 associated with a shunt capacitor 27, and a voltage divider 28. An adjustable rectified control voltage proportional to the voltage of resistor 21 is thereby made available between a terminal and the tap of voltage divider 28. A voltmeter 29 may be connected between the negative terminal of voltage divider 28 and the negative terminal of battery 22 to obtain a visual indication of the magnitude of the difference between the voltages of voltage divider 28 and of battery 22.

A similar indication of the voltage across elec-

trodes 11, 17 and, if direct current is utilized in the measuring circuit, an adjustable rectified control voltage proportional thereto may be obtained by means comprising a potential transformer 31 associated with a rectifier 32, a series reactor 33, a shunt capacitor 34, a voltage divider 35 and a voltmeter 36. The reading of the voltmeter 36 includes the voltage drop in the body of the electrodes 11, 17 and in the portion of the conductors joining the electrode to the primary winding of transformer 31, but such voltage drop is assumed to be negligible compared to the value of the arc voltage.

To regulate the spacing of electrodes 11, 17 automatically in response to the relative values of the voltages measured by voltmeters 29 and 36, armature 19 may be intermittently supplied with rectified current from circuit 15 through a transformer 37 and through an electric valve of any suitable type provided with a control electrode, such as a shield grid thyratron 38. The control grid 39 of thyratron 38 is connected to the cathode 41 thereof through a circuit comprising voltage dividers 33, 35, battery 22, and a current limiting resistor 42. Thyratron 38 is therefore responsive to the differences between the constant voltage of battery 22 and the sum of two control voltages proportional to the voltages across electrodes 11, 17 and across reference resistor 21. The critical potential, above which control grid must be brought to render thyratron 38 conductive, may be varied by impressing a suitable potential on shield grid 43 by means of a suitable source represented by a battery 44.

In operation, current supplied to furnace 14 flows from one of the conductors of circuit 15 through one of the reactors 16 and electrode 11 and reaches the adjacent portion of the electrode 17 in the form of a working arc. The current returns to another conductor of circuit 15 through another arc drawn between another portion of the electrode 17 and electrode 12 or 13. In general, the volt-ampere characteristic of the arc drawn between the electrodes 11, 17, is drooping and nonlinear. It will be assumed that the volt-ampere characteristic, designated 45 in Fig. 3, is the characteristic of the arc between electrodes 11, 17 when the electrode spacing has the desired value.

If the electrode spacing becomes too narrow the volt-ampere characteristic will drop to a corresponding extent as shown by curve 46, for example. If the electrode spacing becomes too wide the volt-ampere characteristic will be boosted a corresponding extent as shown by curve 47, for example. The volt-ampere characteristic of battery 22 is a horizontal line such as line 48 in Fig. 3. The volt-ampere characteristic of resistor 21 is rising. It is curved as shown by curve 49 of Fig. 3, for example, as the resistor is nonlinear. The resistor may be made of any suitable known material, such as clay bonded silicon carbide sold under the trade-mark Thyrite.

Resistor 21 is so adjusted that when the ordinates of curve 43 are subtracted from the ordinates of line 48, the resultant curve substantially matches the shape of curve 45. This means that the resultant curve, if it is not substantially identical to curve 45, at least can be rendered substantially identical to curve 45 by a change in scale. Therefore battery 22 and resistor 21 are connected in a circuit whose output voltage, as measured by voltmeter 29, is related to the working electrode current by a volt-ampere charac-

teristic similar to the volt-ampere characteristic of the working electrodes when the electrodes have a predetermined desired spacing. If the volt-ampere characteristic of the standard of reference is identical to the characteristic of the arc, the voltage measured by voltmeter 29 then is equal to the actual voltage across electrodes 11, 17. If the volt-ampere characteristic of the standard of reference merely matches the electrode characteristic, the actual voltage of the arc is reduced or increased through transformer 31 and voltage divider 35 before being compared with the voltage of the standard of reference. Thyatron 38 is therefore differentially responsive to the output voltage of the circuit of voltage divider 28 and battery 22 and to a voltage equal to or proportional to the voltage across electrodes 11, 17.

The voltage appearing across voltage divider 35 is a measure of the voltage actually present across electrodes 11, 17. The voltage appearing between the negative terminal of battery 22 and the negative terminal of voltage divider 28 is a measure of the voltage which would exist between electrodes 11, 17 if their spacing had the desired value. If the spacing of electrodes 11, 17 is correctly adjusted, voltmeters 29 and 36 therefore will always measure equal voltages regardless of the current intensity through electrodes 11, 12, 13 and 17 and regardless of the positions of electrodes 12, 13 with respect to electrode 17. If the spacing of electrodes 11, 17 is too wide, voltmeter 29 will have a lower reading than voltmeter 36 and if the spacing is too narrow voltmeter 29 will have a higher reading than voltmeter 36.

If the grid control circuit of thyatron 38 is open, the spacing between electrodes 11, 17 may be adjusted manually in accordance with the relative values of the voltmeter readings to bring their voltages to equality. When the control grid circuit of thyatron 38 is closed as shown in Fig. 1, the potential of grid 39 with respect to the potential of cathode 41 is equal to the difference between the output voltage of the standard of reference and a voltage equal or proportional to the voltage of electrodes 11, 17. For the sake of simplicity it will be assumed that the critical potential of grid 39 is equal to the potential of the associated cathode 41.

When the spacing of electrodes 11, 17 is too wide, the voltage dividers and battery 22 bring grid 39 to a potential above the potential of cathode 41, and thyatron 38 therefore becomes conductive to transmit rectified current to armature 19.

The armature drives shaft 20 to lower electrode 11. As a result of the decrease in the spacing between electrodes 11, 17, the voltage of voltage divider 35 decreases relatively to the voltage of voltage divider 28 regardless of the current intensity through electrodes 11, 17. The potential of grid 39 is thereby caused to drop and, when such potential is again below cathode potential, thyatron 38 returns to the nonconductive condition and motor 18 stops. If the voltage dividers are properly adjusted the spacing between electrodes 11, 17 will then have the desired value.

The above described control system is operable only to cause motor 18 to lower electrode 11, but it will be understood that the system may also be arranged to cause the motor to raise electrode 11 when the spacing between electrodes 11, 17 is too narrow. Additional motors and as-

sociated control systems will generally be provided for regulating electrodes 12 and 13.

As shown in Fig. 2, resistor 21 of Fig. 1 may be replaced by an adjustable inductive reactor 49. The reactor is provided with an inductive winding 52. Its core may form two magnetic paths which are symmetrically saturated by a bias winding 51. As a result of the connections of grid 39, thyatron 38 is again additively responsive to the two variable control voltages, of which one is produced in voltage divider 35 in response to the voltage across electrodes 11, 17 and the other is produced in voltage divider 28 in response to the current flow through electrodes 11, 17.

The volt-ampere characteristic of reactor 49 is rising and the volt-ampere characteristic of the combination of current transformer 24, reactor 49, voltage divider 28, and battery 22 is drooping. If reactor 49 is provided with a core in which the magnetic flux reaches the saturation range, the volt-ampere characteristic of the combination is rendered nonlinear and may be adjusted to approximate curve 45 as in the previously considered embodiment.

Bias winding 51 is supplied with a variable direct current from a suitable source such as a battery 53 through an adjustable resistor 54. Variations in the current in bias winding 51 act in a well known manner to vary the saturation of the core or reactor 49 to thereby vary the shape of the volt-ampere characteristic of the reactor. Therefore, bias winding 51 provides a means of readily adjusting the volt-ampere characteristic of the standard of reference to accommodate for working arcs having varying shapes of volt-ampere characteristics.

Although but two embodiments of the present invention have been shown and described, it will be obvious to those skilled in the art that various changes and modifications may be made therein without departing from the spirit of the invention or from the scope of the appended claims.

It is claimed and desired to secure by Letters Patent:

1. In a control system for a pair of relatively movable electrodes between which current is flowing in the form of an arc having a predetermined nonlinear volt-ampere characteristic when the spacing between said electrodes has the desired value, the combination of a motor for controlling the spacing of said electrodes, a resistor having a nonlinear volt-ampere characteristic, means for supplying to said resistor a current proportional to the current flowing through said electrodes, a source of constant voltage, means for connecting said source and said resistor into a circuit having an output voltage related to said electrode current by a volt-ampere characteristic substantially matching said predetermined volt-ampere characteristic, and means responsive to the difference between said output voltage and a voltage proportional to the voltage across said electrodes for controlling the operation of said motor.

2. In a control system for a pair of relatively movable electrodes between which current is flowing in the form of an arc having a predetermined nonlinear volt-ampere characteristic when the spacing between said electrodes has a predetermined value, the combination of a motor for controlling the spacing of said electrodes, an impedance device having a nonlinear volt-ampere characteristic, means for supplying to said device

a current proportional to the current flowing through said electrodes, a source of constant voltage, means for connecting said source and said device into a circuit having an output voltage related to said electrode current by a volt-ampere characteristic substantially matching said predetermined volt-ampere characteristic, and means responsive to the difference between said output voltage and a voltage proportional to the voltage across said electrodes for controlling the operation of said motor.

3. In a control system for a pair of relatively movable electrodes between which current is flowing in the form of an arc having a predetermined nonlinear volt-ampere characteristic when the spacing between said electrodes has a predetermined value, the combination of a motor for controlling the spacing of said electrodes, an impedance device having a nonlinear volt-ampere characteristic, means for supplying to said device a current proportional to the current flowing through said electrodes, voltage divider means connected across said device, a source of constant voltage connected to said voltage divider means to produce an output voltage equal to the voltage of said source less the voltage of a portion of said voltage divider means, said output voltage being related to said electrode current by a volt-ampere characteristic substantially matching said predetermined volt-ampere characteristic, and means responsive to the difference between said output voltage and a voltage proportional to the voltage across said electrodes for controlling the operation of said motor.

4. In a control system for a pair of relatively movable electrodes between which current is flowing in the form of an arc having a predetermined nonlinear volt-ampere characteristic when the spacing between the said electrodes has a predetermined value, the combination of a motor for controlling the spacing of said electrodes, an impedance device having a nonlinear volt-ampere characteristic, means for supplying to said device a current proportional to the current flowing through said electrodes, a source of constant voltage, means for connecting said source and said device into a circuit having an output voltage related to said electrode current by a volt-ampere characteristic substantially identical to said predetermined volt-ampere characteristic, and means differentially responsive to said output voltage and to the voltage across said electrodes for controlling the operation of said motor.

5. In a control system for a pair of relatively movable electrodes between which current is flowing in the form of an arc having a predetermined nonlinear volt-ampere characteristic when the spacing between the said electrodes has a predetermined value, the combination of a motor for controlling the spacing of said electrodes, a resistor having a nonlinear volt-ampere characteristic, means for supplying to said resistor a current proportional to the current flowing through said electrodes, a source of constant voltage, means for connecting said source and said device into a circuit having an output voltage related to said electrode current by a volt-ampere characteristic substantially identical to said predetermined volt-ampere characteristic, and means differentially responsive to said output voltage and to the voltage across said electrodes for controlling the operation of said motor.

6. In a control system for a pair of relatively movable electrodes between which current is flowing in the form of an arc having a predetermined nonlinear volt-ampere characteristic when the spacing between said electrodes has a predetermined value, the combination of a motor for controlling the spacing of said electrodes, a saturable reactor having a nonlinear volt-ampere characteristic, means for varying the volt-ampere characteristic of said reactor, means for supplying to said reactor a current proportional to the current flowing through said electrodes, a source of constant voltage, means for connecting said source and said reactor into a circuit having an output voltage related to said electrode current by a volt-ampere characteristic substantially identical to said predetermined volt-ampere characteristic, and means responsive to the difference between said output voltage and the voltage across said electrodes for controlling the operation of said motor.

7. In a control system for a pair of relatively movable electrodes between which current is flowing in the form of an arc having a predetermined nonlinear volt-ampere characteristic when the spacing between said electrodes has a predetermined value, the combination of a motor for controlling the spacing of said electrodes, a saturable reactor having a nonlinear volt-ampere characteristic, means for varying the volt-ampere characteristic of said reactor, means for supplying to said reactor a current proportional to the current flowing through said electrodes, a source of constant voltage, means for connecting said source and said reactor into a circuit having an output voltage related to said electrode current by a volt-ampere characteristic substantially matching said predetermined volt-ampere characteristic, and means responsive to the difference between said output voltage and a voltage proportional to the voltage across said electrodes for controlling the operation of said motor.

8. In a control system for a pair of relatively movable electrodes between which current is flowing in the form of an arc having a predetermined nonlinear volt-ampere characteristic when the spacing between said electrodes has a predetermined value, the combination of a motor for controlling the spacing of said electrodes, a saturable reactor having a nonlinear volt-ampere characteristic, means for supplying to said reactor a current proportional to the current flowing through said electrodes, a source of constant voltage, means for connecting said source and said reactor into a circuit having an output voltage related to said electrode current by a volt-ampere characteristic substantially matching said predetermined volt-ampere characteristic, and means responsive to the difference between said output voltage and a voltage proportional to the voltage across said electrodes for controlling the operation of said motor.

9. In a control system for a pair of relatively movable electrodes between which current is flowing in the form of an arc having a predetermined volt-ampere characteristic when the spacing between said electrodes has a predetermined value, the combination of a motor for controlling the spacing of said electrodes, an impedance device having a nonlinear volt-ampere characteristic, means for supplying to said device an alternating current proportional to the current flowing through said electrodes, a source of constant unidirectional voltage, means for connecting said source and said device into a circuit

having an output voltage related to said electrode current by a volt-ampere characteristic substantially matching said predetermined volt-ampere characteristic comprising a rectifier connected across said device and a voltage divider connected across said rectifier to be energized at a unidirectional voltage proportional to the voltage of said device, and means responsive to the difference between the said output voltage and a rectified voltage proportional to the voltage across said electrodes for controlling the operation of said motor.

10. In a control system for a pair of relatively movable electrodes between which current is flowing in the form of a working arc having a predetermined volt-ampere characteristic when the spacing between said electrodes has a predetermined value, the combination of a motor for controlling the spacing of said electrodes, an impedance device having a nonlinear volt-ampere characteristic, means for supplying to said device an alternating current proportional to the current through said electrodes, a rectifier connected across said device, a voltage divider having an adjustable tap and a pair of terminals connected to said rectifier, a source of constant unidirectional voltage, means for connecting the positive terminal of said source to said tap to produce between the negative terminal of said voltage divider and the negative terminal of said source 30 an output voltage related to said electrode current by a volt-ampere characteristic substantially matching said predetermined volt-ampere characteristic, and means responsive to the difference between said output voltage and a rectified volt- 35

age proportional to the voltage across said electrodes for controlling the operation of said motor.

11. In a control system for a pair of relatively movable electrodes between which current is flowing in the form of an arc having a predetermined nonlinear volt-ampere characteristic when the spacing between said electrodes has a predetermined value, the combination of a motor for controlling the spacing of said electrodes, an impedance device having a nonlinear volt-ampere characteristic, first means for supplying to said device a current proportional to the current flowing through said electrodes, a source of constant unidirectional voltage, second means connected to said device for producing a first variable unidirectional voltage proportional to the voltage of said device, third means connected to said electrodes for producing a second variable unidirectional voltage proportional to the voltage across said electrodes, and means for controlling the operation of said motor comprising means connected to said source and to said second and third means responsive to the difference between the voltage of said source and the sum of said 15 variable unidirectional voltages.
